CLAIM

The ornamental design for a bottle holder, as shown and described.

DESCRIPTION

FIG. 1 is a top and front perspective view of a bottle holder showing our new ornamental design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an environmental top and front perspective view of a bottle holder showing my new ornamental design.

The broken lines of FIGS. 1–8 are for illustrative purposes only and form no part of the claimed design.

1 Claim, 5 Drawing Sheets(56)
